UNITED STATES PATENT OFFICE.

JOHN N. HAKE, OF LITTLESTOWN, PENNSYLVANIA.

CLAMP.

No. 840,620.

Specification of Letters Patent.

Patented Jan. 8, 1907.

Application filed March 16, 1906; Serial No. 306,456.

to all whom it may concern:

Be it known that I, JOHN N. HAKE, a citizen of the United States, residing at Littlestown, in the county of Adams and State of Pennsylvania, have invented a new and useful Clamp, of which the following is a specification:

This invention relates to devices employed for clamping two bodies together, more particularly for clamping two wires.

The device may be employed for clamping together the ends of two wires, for clamping two wires intermediate the ends, for coupling two wires in transverse relations, and the like.

The device may be employed for connecting telegraph, telephone, or similar wires in their various arrangements and locations and for the purpose of illustration is shown applied in a variety of forms.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

In the drawings, Figure 1 represents the improved clamping device applied to the coupling of two wires lined parallel to each other. Fig. 2 is an end elevation of the clamping device with the wires in transverse section on the line 2 2 of Fig. 1. Fig. 3 is an end elevation of the form of clamping device employed for securing the strand-wires of wire fences to the posts. Fig. 4 is a side elevation of the structure shown in Fig. 3. Fig. 5 is a front elevation of the structure shown in Figs. 3 and 4. Fig. 6 is a view representing the manner of employing the clamping device for suspending telegraph and telephone cables, electric-light conductors, and similar structures. Fig. 7 is a side elevation, and Fig. 8 is a plan view, of a modified form of the clamping device. Fig. 9 is an elevation of a fence-post with a plurality of the clamping devices arranged thereon in position to support the strand-wires, Fig. 9 being a further illustration of the means of applying the structure shown in Figs. 3, 4, and 5. Fig. 10 is a view of portions of a

modified form of fence-post with the improved clamping devices applied.

The improved device comprises in general two U-shaped sheet-metal plates 10, 11, preferably galvanized or otherwise treated to protect the metal from oxidation and interlapping from opposite sides—that is to say, with the terminals 12, 13 of the sides of the inner plate within the fold of the outer plate 15 and adjacent to the bend 14 of the same, and with the terminals 15, 16 of the outer plate bearing over the bend 17 of the inner plate. The two plates thus arranged are clamped together by transverse bolts 28 or similar devices, and any number of bolts or other securing means may be employed; but generally two will be found sufficient, as in Fig. 1; but three or more may be employed, if preferred, as in Figs. 7 and 8. The wires 18 to be clamped are represented at 19 and are disposed within the folds of the plates and between the clamping-bolts and the bends of the plates, as shown in Fig. 2. By this simple arrangement it will be obvious that the wires may be very firmly clamped and immovably held between the plates and cannot be removed therefrom except by entirely separating the plates and will not be released or become accidentally detached by the loosening of the clamping-bolts.

As above stated the improved clamping means may be employed for a variety of purposes. For instance, in Fig. 1 the device is shown employed for securing two wires together and also for connecting guy-wires thereto, the latter indicated at 20.

In the arrangement shown in Fig. 1 the end of the wire 19 is coiled at 21 around the wire 18 at one end of the clamping-plates, and the wire 18 is coiled at 22 around the wire 19 at the opposite end of the clamping-plates, the wire 18 being continued laterally to from the guy-wire 20. This arrangement may also be employed when it is desired to connect a branch wire in telegraph and telephone structures for any required purpose. The structures shown in Figs. 1 and 2 may also be employed wherever it is desired to couple two wires either at their adjacent ends or intermediate the same, as will be obvious.

In Figs. 3, 4, 5, and 9 there is shown the clamping device arranged for supporting strand-wires upon fence-posts, and in this arrangement the ends of the outer plate are of greater length than the inner plate and diverge, as at 23, 24, for bearing against the

post represented at 25. In the arrangement shown in Figs. 3, 4, and 5 one wire only will be required for the plates, (represented at 26,) this single wire being attached at the 5 ends to the post 25 and extending through a plurality of the pairs of clamping-plates, there being as many of the pairs of clamping-plates as there are strand-wires 27, the latter passing through transverse apertures in the 10 plates, preferably between the clamping-bolts 28, as shown. By this simple means the strand-wires are firmly supported in position relative to the post.

In Fig. 6 the manner of employing the improved clamping device for suspending a cable from a stay-wire is shown, the stay-wire being represented at 29, the cable at 30, and with a bridging-wire 31 coupling a pair of the clamping-plates disposed upon the 15 stay-wire with a pair of the clamping-plates disposed upon the cable, the latter necessarily larger than the clamping-plates upon the stay-wire to correspond to the increasing size of the cable.

In Figs. 7 and 8 the device is shown provided with three of the clamping-bolts, which arrangement will be employed where it is desired to couple the wires with greater firmness or where the wires are subjected to 20 abnormal strains.

The device is simple in construction, can be inexpensively manufactured, readily applied, and will hold the wires against all displacements so long as the holding means 25 30 are not entirely detached.

It will be obvious by this arrangement that when bolts are employed as the securing means the binding-nuts may be loosened or almost entirely removed without danger of 35 the displacement of the wire, as the plates cannot be separated so long as the bolts are in position through the plates.

In Fig. 16 another form of post is shown combined with the improved clamping devices, the post being constructed from an 40 45

elongated U-shaped rod 32 of sufficient strength, with the spaced ends inserted into the ground or into a suitable supporting-base and with the clamping devices embracing the spaced sides of the rod with a central aperture to receive the strand-wire 27. The clamping devices are substantially the same as shown in Figs. 7 and 8, except that they are larger and wider, as the U-shaped rod 32 is of larger gage and with the sides spaced 50 55 farther apart, but otherwise the construction is substantially the same.

Having thus described the invention, what is claimed is—

1. A device of the character described comprising an inner and an outer plate, said plates being oppositely disposed and the inner plate having its end portions oppositely bowed and fitting snugly within the bend of the outer plate, and clamping means extending through the inner and outer plates between their bends and terminals.

2. A device of the character described comprising an inner and an outer plate, said plates being oppositely disposed and each 70 folded at the center, the inner plate having its terminals bowed in opposite directions to constitute clamping-jaws fitting snugly within the bend of the outer plate, said plates having alining apertures therein between their 75 bends and terminals, and a clamping device extending through the apertures.

3. A device of the character described comprising a folded spring inner clamping-plate, a folded spring outer clamping-plate, 80 and means extending through said plates for contracting them.

In testimony that I claim the foregoing as my own I have hereto affixed my signature in the presence of two witnesses.

JOHN N. HAKE.
